(57) **CLAIM**

The ornamental design for a remote control car, as shown and described.

DESCRIPTION

FIG. 1 is a front, left, and top perspective view of a remote control car, showing my design.

FIG. 2 is a rear, right, and bottom perspective view thereof.

FIG. 3 is a front elevation view thereof.

FIG. 4 is a rear elevation view thereof.

FIG. 5 is a left side elevation view thereof.

FIG. 6 is a right side elevation view thereof.

FIG. 7 is a top plan view thereof.

FIG. 8 is a bottom plan view thereof.

FIG. 9 is a partial enlarged view of FIG. 1 comprising a wheel of the remote control car.

FIG. 10 is a partial enlarged view of FIG. 1 comprising a part of the top cover of the remote control car.

FIG. 11 is a partial enlarged view of FIG. 1 comprising another part of the top cover of the remote control car; and, FIG. 12 is a partial enlarged view of FIG. 2 comprising a nozzle of the remote control car.

The dash-dot broken lines represent the boundaries of the enlarged partial views of FIGS. 9-12. All other broken lines represent portions of the remote control car that form no part of the claimed design. None of the broken lines form a part of the claim.
